BOOK CONSTRUCTION

Frank Stanley Schade, Holyoke, Mass., assignor
to National Blank Book Company, Holyoke,
Mass., a corporation of Massachusetts

Application November 23, 1934, Serial No. 754,456

1 Claim. (Cl. 281—19)

This specification will disclose an improved book construction of the kind having a back portion and two hinged covers, between which all the pages, or filler, may be bound or unbound as desired, for changing the book contents. This kind of book construction is known and appears in various prior art forms. The new form to be disclosed is one having certain combinations with definite advantages, as will appear from the following description.

Fig. 1 is a plan view of book covers and back portion without contents;

Fig. 2 is a plan view of the book pages arranged for insertion as the book contents;

Fig. 3 is an edge view of the book with all elements assembled as a unit;

Fig. 4 shows a rod suitable for fastening the book contents in the book binder;

Fig. 5 is a plan and

Fig. 6 is a sectional view on line 6—6 showing the metal plate mounted in the back portion of the binder; and

Fig. 7 is a detail view showing the assembly of the metal parts only.

The book binder of Fig. 1 is technically known as a case. It consists of the two covers 1 and 2 hinged to the curved back portion 3, all in one unit. In making up such a case for this invention, the curved metal plate 4 of Fig. 5 is fastened into the back portion, preferably by laminating it with the usual binding strips on the outside, as book binders will understand. Spaced bridges 6 are stamped out of this metal and extend upwardly so as to make small open arches on the inside of the back portion, see Fig. 6. This arrangement completes the case or binder seen in Figs. 1 and 3.

The book contents of Fig. 2 is an arrangement of sheets or pages 7, with spaced holes along their binding margins. A single helically coiled binding wire 8 is threaded through these holes, the wire having the pitch equal to the space between the holes. The binding of paper pads in this way, as shown in Fig. 2, is well known and widely used. Such a pad is frequently made up with covers fastened or hinged on the coiled wire 8 in the same way as the individual sheets. Such covers, however, are merely outside sheets of the pad.

The pad of Fig. 2 is used for the contents or unit filler in combination with the binding case described and seen in Fig. 1. Such pad is inserted with the coiled wire 8 fitting along the inside of the binder back, see Fig. 3. The spaced metal arches or bridges 6 are preferably dimen-

sioned to fit, each between two adjacent coils of the wire 8. That is to say, the width of each bridge or arch is about equal to the pitch distance of the wire. This arrangement helps to support the long binding wire in the book back. 5 When the pad is thus inserted, the rod 9 of Fig. 3 is pushed along the back portion inside the coils 8 and under each bridge 6, which bridge extends far enough above some of the coils to take the rod, as in Fig. 7. The book contents are in 10 this way removably fastened in the binder case, see Fig. 3.

The combination of parts is a simple and effective one to make a very useful book. All that is added to the binder case, in the disclosed and 15 preferred form, is a single metal stamping 4. The pad or book contents of Fig. 2 is of a highly desirable and known form of book unit. The binder case and its contents are brought into or out of book combination by the mere insertion 20 or removal of one rod 9 to engage or disengage the two main elements. The rod may be so placed as to fit rather snugly between the binding wire coils 8 and the spaced arches 6. If this is provided for, as well as for a rather snug fit 25 of the width of the arches between the coils, the assembly will be made in the preferred form. There will be enough spring action between the parts all along the back, due particularly to the 30 springy nature of the coiled wire, as to hold everything without the shifting about in use which so often gives a "sloppy," unsubstantial impression to removable binders. The new arrangement gives a removable binder for the particular kind of book filler so highly desirable to use on account of the inexpensive and efficient way in 35 which the pages are bound to turn over easily and lie flat. The whole book in the form now disclosed and seen in Fig. 3 is a new and useful article in which the elements all coact. 40

Having described the invention and how it may be practiced, the following claim is made for its protection.

I claim:

In a book structure of the kind in which the 45 filler sheets are hung on the closely spaced coils of a single binding wire and fastened to the back panel of the binder case by a rod inside the coils and fastened to the back panel, that construction in which the back panel is curved transversely, a 50 sheet metal stiffening plate built into the back panel over its whole area and shaped to hold the back panel form, a series of arches spaced along the whole length of the back panel struck up from the sheet metal of the back panel, the arches 55

together defining a path for the fastening rod, each arch of a width to extend upwardly between two of the wire coils and the arches being spaced one from another, for many coils to nest in the curved back panel between them, but all held by the rod engaged under said arches and bearing downwardly against all of said coils over the whole length of the back panel whereby the sheet

metal plate functions to both hold the curved form of the back panel as a functional part of said back panel and as a rod holding means by reason of its integral arches to nest the wire coils closely in said curved back panel under the rod 5 and between the arches.

FRANK STANLEY SCHADE.
